UNITED STATES PATENT OFFICE.

FRANK W. WOOD, OF NEW YORK, N. Y.

BOILER-TIMING DEVICE.

1,038,495.

Specification of Letters Patent. Patented Sept. 10, 1912.

Application filed November 7, 1911. Serial No. 659,025.

To all whom it may concern:

Be it known that I, FRANK W. WOOD, a citizen of the United States, residing at New York, in the county of New York and State 5 of New York, have invented new and useful Improvements in Boiler-Timing Devices, of which the following is a specification.

This invention relates to electric timing devices for signaling in the systematic firing 10 of boilers, and is especially adapted for use on board ship.

On board ship it is particularly desirable that the boilers be fired regularly and in alternate groups to preserve a uniform 15 steam pressure since the opening of the doors of too many of the boilers at one time are likely to cause serious falls of steam pressure just when it is most desirable that the pressure should be maintained. Furthermore, by firing according to the regular 20 uniform system, the amount of fuel used is greatly reduced, by reason of the fact that the fuel is most economically used. Further advantage results by reason of the fact that 25 the firemen can do better work for longer periods of time, their efforts being made to count for the most. While of the particular relation and adaptation stated, however, it will be evident upon an understanding of 30 my invention that it may be used in other situations with the same and perhaps greater advantage. Such timing devices are not broadly new, and my invention has to do with the production of a timing device 35 which is positive, reliable and accurate in its indications, which may be most readily adjusted as regards the number of boilers which it indicates shall be fired at any given time, and as to the interval which is to pass 40 between the successive firings. My aim has been to secure these ends in a system comprising mechanical construction which is simple, light in weight, and relatively cheap to manufacture.

45 To these ends my invention comprises a motor operated transmitter, usually located in the engine room, and associated with transmission lines leading to indicators at the several boilers, or in the several fire 50 rooms in which they are located. This transmitter comprises a mechanism having switch contacts adapted to be operated by a motor to connect the transmission lines to a source of power to actuate signals for the 55 boilers in the rooms. In each transmission line there is located an individual switch by

which any particular indicator may be disconnected from the transmitter and hence removed from the control of the timing device.

60

Further, and of chief importance, my invention comprises timing contacts adjustable in position with respect to each other and the time of operation, and adapted to be operated by an automatically reversing 65 substantially constant speed electric motor, the said timing contacts controlling the operating circuit of the motor of the transmitter, and said transmitter carrying contacts adapted automatically to reverse the afore- 70 said constant speed motor, thereby to cause the timing contacts to be alternately operated.

Further structural details of my invention and further advantages resulting therefrom 75 will be apparent from the following detail consideration of it.

In the drawings disclosing one embodiment of my invention, it being of course understood that my invention may be given 80 a number of forms without departing from its generic spirit; Figure 1 is a general diagrammatic illustration of my invention showing the electric circuits of all of the devices including the connections from the 85 source of power and to the indicators. Fig. 2 is a central longitudinal and vertical section of the timing device and transmitter. Fig. 3 is a front elevation of the same. Fig. 4 is a front elevation of the dial on which 90 the time intervals are marked, and with respect to which the device is adjusted. Fig. 5 is a detail sectional view of the timing apparatus.

95 Referring to the drawings, in which similar characters designate like parts throughout the several views, and first to Fig. 1, A, B, C and D designate receiving indicators of any known or desired type, which indicators are located in the several boiler rooms at any 100 convenient place. Located in the engine room, or in any other suitable place for control by the proper parties, is the motor operated transmitting and timing device designated generally 10. Conductors 11 are led from the indicators A, B, C and D to the device 10.

105 The motor operated transmitter comprises sets of movable switch contacts 12, 13 and 14, and 15, 16 and 17, and a motor device, at 110 present in the form of a relay 18 adapted to operate first one set 12, 13, 14 into a coöper-

ating set 12', 13', 14' of the fixed contacts, and then the other set 15, 16 and 17 into a corresponding set of contacts 15', 16' and 17'. Connections are made from the lines 11 through individual switches *a*, *b*, *c* and *d* to the left hand contact 12', while other connections may be made from the other sets of indicators through conductors 11' and individual switches *e*, *f*, *g* and *h* to the extreme right hand contact 17'.

10 The transmitter is connected with a source of power *S* through the conductors 19 and 20, conductor 19 being the positive line and conductor 20 the negative line. A common negative conductor 21 is connected with each of the indicators A, B, C and D.

15 The movable contacts of the transmitter are carried upon a pivoted cross bar 22 to which are fixed armatures registering with magnets 23 and 24 of the relay 18 to work the bar 22 and bring, first the movable contacts on one side into connection with the corresponding fixed contacts, and then the movable contacts on the other side with their 20 corresponding fixed contacts. As shown, the contacts on the left hand side are in engagement, and an electrical circuit may be traced from the positive line of the source of power 19 through the contacts 12' and 12, the conductor 25 and switches *a*, *b*, *c* and *d*, and conductors 11, then through the indicators back to the negative line 20 by way of the common conductor 21. Thus each of the indicators A, B, C and D are energized. These 25 may be thus on the starboard side of the ship. When the bar 22 is oscillated, by the energization of the magnet 24, to bring the right hand contacts into engagement a similar circuit may be traced from conductor 19 through the contacts 17' and 17, the conductor 26 to the intermediate individual switches *e*, *f*, *g* and *h*, and then by way of the conductors 11' to another set of indicators which may be located on the port side 40 of the ship.

45 The magnets 23 and 24 of the relay 18 are energized, to cause the aforesaid operation, through the control of the timing device. This timing device comprises stationary contacts 27 and 27', and movable contacts 28 and 28', the latter being mounted upon a shaft 29 for angular adjustment to space the same at various distances from the stationary contacts. Collector rings 30, 30' 50 are disposed on the shaft 29 and are in electrical connection with the movable contacts 28 and 28'. A connection is made between the contacts 27 and 28 and the positive conductor 19, through conductor 31 connecting 55 directly with contact 27 and with contact 28 through a brush 32 bearing on ring 30. A conductor 33 leads from the contact 27' to the magnet 24 of the relay 18, while conductor 34 leads from a brush 32', bearing 60 on ring 30', to the other magnet 23 of the 65

relay 18. A motor 35 is adapted to be actuated from the source of power *S*, alternately through the contacts 13, 13' and 16, 16', reversing the motor 35 upon each oscillation of the bar 22. The motor 35 is adapted to revolve at about 1,600 revolutions per minute, and is connected by a suitable reduction gearing 36, preferably worm gearing as shown, to a shaft 29' to rotate the latter at approximately one-fifth of a revolution per minute. The shaft 29' is disposed in longitudinal alinement with and concentric to the shaft 29, as may be understood from Figs. 2, 3 and 5. The shaft 29' carries an arm 37 provided at its outer end with an insulated laterally extending abutment 37', alternately engaging the contacts 27 and 28'. When the abutment 37' strikes the contact 27 the circuit through the contacts 27 and 27' is closed to energize the magnet 24 of the relay 18, drawing the adjacent end of the bar 22 down and closing the right hand contacts of the relay. When the abutment 37' strikes the contact 28' the circuit is closed through the contacts 28 and 28' 80 and the magnet 23 of the relay, drawing down the adjacent end of the bar 22 and closing the left hand contacts of the relay. The motor is provided with a normally excited field 38 connected directly across the lines 19 and 20 of the source of power *S*. With the contacts 12, 13 and 14 in the position shown, the motor operates at a substantially constant speed in one direction. We will assume that this direction is such as 85 to provide a counter-clock wise rotation of the shaft 29', the arm 37 having closed the contacts 28 and 28' and energized temporarily the magnet 23 of the relay 18. Under these conditions the motor is operated by a 90 current which passes from the conductor 19 through contacts 13' and 13, through conductor 38' and the armature of the motor 35, through conductor 39 and cross-connection 40, contacts 14' and 14 and back to the conductor 20. As soon as the abutment 37' engages the contact 27 the circuit of the magnet 24 is closed, as aforesaid, and connections are broken on the left hand side of the relay 18, and are made on the right hand side, 100 the armature circuit of the motor 35 thus being reversed. Current passes from the line 19 through the contacts 16' and 16, through the conductor 39, armature of the motor 35, conductor 38', the cross-connection 41 to contacts 15' and 15, and back to the line 20. Thus the operating arm 37 of the timing contacts has its movement reversed, and it thereupon moves back at a constant speed 105 to close the contacts 28 and 28' once more, whereupon the cycle of operation described is repeated. Thus by this simple device the groups of indicators A, B, C, and D, and those associated with the conductors 11', are 110 alternately energized, contact being first 115 120 125 130

closed on one side through the contacts 12 and 12', and then on the other side through the contacts 17 and 17'. Lights 42 and 43, which are preferably of different colors, are provided in connection with contacts 12 and 12', and 17 and 17' for indicating which groups of indicators are energized at any particular time. Preferably one of these lights is red, indicating port, while the other 10 light is green, indicating starboard.

From the general system just described it will be apparent that first one group of the indicators and then the other group will be energized at regular intervals. An adjustment of the interval is provided, and this adjustment will be more fully understood from a consideration of the practical structural embodiment in Figs. 2, 3, 4 and 5. Referring to these figures, 44 designates a casing having upper and lower compartments, the upper one of which is closed by a hinged cover 45. The hinged cover 45 is held closed by special head screws that can be loosened only by a complementary key to prevent access by unauthorized persons. A suitable packing is interposed between the cover 45 and the casing 44 to seal the compartment.

On the inside of the cover 45 are secured the elements of the transmitting and timing device. The motor 35 is secured to the upper end of the cover, the shafts 29 and 29' to the middle of the cover by a suitable casing 45^a which also supports the contacts 27 and 27', and to the lower end of the cover is attached the relay 18. The brushes 32 and 32' are fixed to the frame 45^a, registering with the rings 30 and 30' on the shaft 29, and bearing against the same at opposite sides. The outer end of the shaft 29 is reduced, as 40 at 47, such reduced portion of the shaft 29 projecting through the cover 45 of the casing 44, and carrying upon this outer end a fixed pointer arm 48, by which the shaft 29 is adjusted to move the contacts 28 and 28' 45 in a circular direction and to any desired position toward or from the contacts 27 and 27'. The cover 45 is provided at its middle with a circular depression providing a dial in back of the pointer 48, the dial having a 50 concentric circular boss with a dove-tailed groove 49 receiving the correspondingly formed head of a clamping bolt 50. The bolt 50 passes outwardly through the pointer 48, adjacent its outer end, and is surrounded 55 by an inwardly extending boss on the pointer registering with, and bearing against, the boss of the dial. A preferably knurled thumb nut 51 is carried upon the outer end of the bolt 50, and binds against the pointer 60 to force the latter against the dial when adjusted. The dial has a scale 52 laid off in minutes and seconds, preferably ten minutes, thereby admitting of the separating of the pairs of contacts 28, 28' from the pairs 65 of stationary contacts 27, 27' distances pro-

ducing various time intervals up to ten minutes between the reversals of the motor 35.

The arm 37 and contacts 28 and 28' are so set with respect to each other and with respect to the scale 52 that the scale markings represent true time intervals, as determined by the speed of the motor 35. 70

The lower compartment of the casing 44 contains the line switches *a*, *b*, *c*, etc., the fuses and such other apparatus needed for the control of the connections from the source of power. A small hinged cover 53 closes the lower compartment and is held in such position by dogs 54, or the like, admitting ready access to the switches. 75

Having fully described my invention, what I claim is:—

1. In a timing device for electric circuits, a plurality of switches included in the circuits, a relay for alternately closing and opening the circuits in separate groups, a pair of stationary contacts in circuit with one side of the relay, a pair of movable contacts adjustable toward and from the stationary contacts and in circuit with the opposite side of the relay, a closing arm movable between the pairs of contacts to alternately close the same and operate the relay, a reversible motor for actuating the closing arm, and a motor circuit controlled by the 90 relay for reversing the motor. 95

2. A timed signal system comprising a transmitter having fixed and movable contacts and a swinging arm for alternate engagement with the contacts, means upon 100 the transmitter for adjusting the movable contacts toward and from the fixed contacts, a motor associated with the transmitter to swing the arm, switches controllable by the fixed and movable contacts to reverse the 105 motor, and separate groups of electric circuits associated with the switches whereby the groups of circuits are alternately opened and closed.

3. A timed signal system comprising a 110 transmitter having spaced circuit closing devices, means for varying the space separating said devices, a swinging arm for alternate engagement with the said devices, a motor for moving said arm, switches controllable by the circuit closing devices to reverse the motor, and separate electric circuits associated with said switches whereby said switches are alternately opened and closed. 115

4. An electric timing device comprising a source of power, a motor driven from the source of power, groups of electric circuits, a relay arranged in circuit with the source of power and the motor for reversing the 125 motor and alternately closing the groups of circuits, spaced pairs of contacts associated with the relay to operate the same and effect the reversing of the motor, one pair of contacts being movable with respect to the op- 130

posite pair, and closing means actuated by the motor adapted for alternate engagement with the contacts.

5. In an electric timing device, a source of power, a motor driven from the source of power, groups of electric circuits, a pole changing relay arranged in circuit with the source of power and the motor whereby the latter is reversed and being associated with 10 the groups of circuits to alternately close the same, a movable arm having operative connection with the motor to swing the arm, fixed contacts arranged in the path of the arm, adjustable contacts arranged in the 15 path of the arm and adapted for movement toward and from the fixed contacts, said contacts being in circuit with the opposite sides of said relay, and means for adjusting said movable contacts.
- 20 6. A timing device for signal systems comprising a reversible motor, a transmitter in operative connection with the motor, a swinging arm carried by the transmitter, fixed contacts in the path of said arm, adjustable contacts in the path of said arm and adapted for movement toward or from the fixed contacts to vary the time between the operation of the same, and signal circuits controllable through the contacts for 25 alternately actuating the signals.
7. In combination with groups of electric indicator circuits, separate groups of switches for closing the circuits, a relay associated with the switches for alternately 30 opening and closing the groups, a motor, an arm driven by the motor, and pairs of contacts in the path of the arm adapted to be alternately closed by the same and being associated with the opposite sides of the relay to actuate the latter, said motor being 35 closed in circuit by said relay whereby the motor is reversed.
8. In combination with a plurality of indicator circuits, opposed groups of switches 40 associated with the circuits to control the same, a relay operatively connected with the switches to alternately open and close the groups of the same, a pair of stationary contacts in circuit through one side of the relay, a pair of adjustable contacts in circuit with 45 the opposite side of the relay, a motor, a motor circuit controllable by the relay for reversing the motor, and an arm operated by the motor to move between the pairs of contacts to alternately close the same.
- 50 9. The combination with a plurality of indicator circuits and switches arranged in opposed groups for closing the circuits, of a relay associated with the groups of switches 55 to alternately open and close the same, a pair of contacts in circuit with one side of the relay to close the switches at that side upon the closing of the contacts, a pair of

adjustable contacts in circuit with the opposite side of the relay to close the opposite switches upon the closing of the adjustable contacts, said adjustable contacts being movable toward and from the fixed contacts to vary the distance therebetween, a movable arm adapted to travel between the 70 pairs of contacts for alternately closing the same, and a motor for actuating said arm, said motor being closed in circuit by said relay to reverse the motor.

5. A timing device comprising groups 75 of opposed switches for closing groups of circuits, a relay arranged between the switches for alternately opening and closing the same, a motor, a motor circuit associated with opposed switches in said groups 80 for reversing the motor, an arm movable by the motor, fixed contacts in the path of the arm in circuit with one side of the relay, adjustable contacts movable toward and from the fixed contacts, and in the path of the 85 arm and being in circuit with the opposite side of the relay, and manually operable means for the movable contacts whereby the latter may be moved toward and from the fixed contacts to vary the time interval of 90 the movement of the arm between the contacts.

11. In a timing device for electric circuits, separate groups of switches for closing the circuits, closing means for alternately closing the switches in separate groups, spaced pairs of contacts associated with the closing means to effect the closing of the opposite groups of switches, a motor-driven arm movable between the contacts to alternately close the same, and a motor circuit associated with said closing means to reverse the movement of said arm.

12. In a timing device for electric signal systems, a plurality of circuits, separate 105 groups of switches for closing the circuits, one of said circuits being a motor circuit, a motor in said circuit adapted to be reversed upon the alternate closing of said groups of switches, an arm operated by the motor, 110 fixed contacts in the path of said arm, a relay associated with the fixed contacts to close one group of said switches, adjustable contacts in the path of said arm associated with said relay to close the opposite group 115 of switches, and means for moving said adjustable contacts toward and from the fixed contacts to vary the time interval between the closing of the same.

In testimony whereof I have hereunto set 120 my hand in presence of two subscribing witnesses.

FRANK W. WOOD.
